Primary Examiner — Katherine Glennon

(57) **CLAIM**

The ornamental design for a watch with case and integrated band, as shown and described.

DESCRIPTION

FIG. 1 is a first perspective view of a watch with case and integrated band showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the watch with case and integrated band in which the design is embodied that form no part of the claimed design.

1 Claim, 8 Drawing Sheets
